WILLIAM E. HARKNESS, OF EAST ORANGE, NEW JERSEY, ASSIGNEE, BY MESNE
ASSIGNMENTS, TO HALL SWITCH & SIGNAL COMPANY, A CORPORATION OF MAINE.

PLURAL SELECTIVE SIGNALING DEVICE.

1,183,193.

Specification of Letters Patent. Patented May 16, 1916.

Application filed September 12, 1912. Serial No. 719,340.

To all whom it may concern:

Be it known that I, WILLIAM E. HARKNESS, residing at East Orange, in the county of Essex and State of New Jersey, have invented certain new and useful Improvements in Plural Selective Signaling Devices, of which the following is a specification.

This invention relates to a high speed selector for use on telephone and telegraph lines, whereby signals at various points along the line may be selectively operated without interference of electrical impulses impressed upon the line.

The several selectors on the line are preferably controlled by an automatic sender comprising a movable contact adapted to send impulses at rapid intervals, said impulses being of relatively short and relatively long duration, as is common in the art. By a properly selected series of relatively long and short impulses the selector at any given station may be called without making contact through any other selector on the line.

25 The present invention, while applicable to various forms of selective signaling devices, as embodied herein, involves certain improvements over structures of the general type exemplified for instance in several patents and applications of one Edwin R. Gill and particularly his pending application Serial No. 686,798, filed March 28, 1912.

The principal object sought to be attained is to improve such structure whereby, in its 35 unitary formation, it may be made adaptable for closing any selected one of a plurality of signal circuits in response to a selected series of short and long impulses.

Another object is to improve the construction, manner and arrangement of the contact making parts whereby they are made more positive and whereby a number of 40 separate contacts may be mounted and independently controlled from a single control member.

Other objects and aims of the invention, more or less broad than those stated above, will be in part obvious and in part specifically referred to in the course of the following description of the elements, combinations, arrangements of parts, and applications of principles constituting the invention, and the scope of protection contem-

plated therefor will be indicated in the appended claims.

55 In the accompanying drawings, which are to be taken as a part of this specification, and in which I have illustrated a merely preferred form of embodiment of the invention, Figure 1 is a side elevational view 60 of a selector constructed in accordance with this invention, the protecting hood thereof being removed; Fig. 2 is a view similar to Fig. 1, but being taken from the opposite side of the device; Fig. 3 is a top plan view 65 of the parts shown in Fig. 1; Fig. 4 is a front elevational view, the base portion being shown in transverse section; Fig. 5 is a transverse, vertical, sectional view taken substantially on the plane of line 5—5 of 70 Fig. 3 looking in the direction of the arrow; Fig. 6 is a longitudinal, vertical, sectional view taken on the plane of line 6—6 of Fig. 4 looking in the direction of the arrow; Fig. 7 is a side, elevational view, 75 parts being omitted and parts being shown in vertical section substantially on the plane of line 7—7 of Fig. 4, looking in the direction of the arrow, the protecting hood being illustrated in position in section; Fig. 8 is 80 a detail, fragmentary, elevational view of the controlling ratchet wheel, which is adapted to be stepped up by electrical impulses; Fig. 9 is a fragmentary, perspective view of the contact making mechanism, and 85 illustrating the application of a slight modification thereto; and Fig. 10 is a detail perspective view of the lever pawl for engaging the wheel shown in Fig. 8.

90 Referring to the drawings by numerals, 1 indicates a base, of porcelain or the like, upon which is supported the protecting hood 2, preferably of glass. Within the hood 2, and supported upon the base 1, is the framework of the selector, generally designated as 95 3. This framework comprises spaced side members 4 and 5 and between these is journaled a horizontal shaft 6 carrying a ratchet control wheel 7. The shaft 6 is impelled in the direction of the arrow (Fig. 6) by the 100 hair spring 8. An electro-magnet 9 acts, through the armature 10, bowed spring 11, and connecting rod 12, to operate an impelling lever 13. An impelling pawl 14 is pivoted to the free end of the lever 13 and is 105 provided with a short arm 15 against which

bears leaf spring 16 for directing the lower end of the pawl into the successive teeth of the wheel 7. A stop 17 is provided to limit the downward movement of the pawl 14. 5 Energization of the magnet 9 straightens the spring 11 and causes the lever 13 to swing downward on its pivot at 18, and the impelling pawl 14 engages the wheel 7 and moves the same one tooth forward. When 10 the magnet is deenergized the spring 11, through the rod 12, and lever 13, lifts the pawl 14 back to its normal position. A retaining pawl 20, projecting laterally from a lever arm 21, engages the teeth of the 15 wheel 7 to prevent return of said wheel to normal under the influence of spring 8. The arm 21 is fixed rigidly to an inclined shaft 22 rockably mounted in bearings in the opposite side pieces 4 and 5 of the frame, 20 said shaft being movable endwise upon elongated journals to facilitate bodily movement of the lever 21 sidewise to disengage the pawl 20 from the teeth of the wheel 7. The inclination of the shaft 22 causes the 25 same to drop by gravity toward its lower end and thereby causes the return of the pawl 20 into engagement with the teeth of the wheel as will be hereinafter explained.

The action of the control wheel and its 30 driving parts may be described substantially as follows: When the wheel is at normal, and before a call is begun, any rapid impulses impressed upon the line will produce only a back and forth motion of said wheel 35 through the space of a single tooth, but when a call is begun, a long impulse is given to prepare the wheel for action. Thereafter a selected series of codal impulses will cause the wheel to move forward step by step until 40 the phase of movement has been completed. In order to effect this result, in the present instance, as heretofore, the wheel 7 is provided with two types of teeth which may be 45 designated "upper contact" and "lower contact" teeth, that is, certain of the teeth are beveled off at their bases so that only the upper portions thereof present a holding surface to the pawl 20, and others of said teeth are beveled off at their upper portions 50 whereby only the base portions present a holding surface to the pawl 20. These two types of teeth are indicated at 23 and 24 in Fig. 8, 23 designating a "lower contact" tooth and 24 indicating the "upper contact" 55 teeth. There is also provided upon the wheel 7 a tooth 25, which is beveled both top and bottom, so that no portion thereof will present a holding surface to the pawl 20. There is also provided a tooth 26 having its upper portion cut entirely away.

Fig. 6 shows the normal position of the parts, and in this position the lever 21 is supported in an elevated position so that the pawl 20 is raised out of engagement with 65 the teeth of the wheel. A catch 27, on the

lever 21, stands above a hook 28 fixed upon a rock shaft 29. This hook, by engaging the catch 27, maintains the pawl 20 elevated so that, while it will form a holding engagement with "upper contact" teeth 24, it 70 however can not hold the "lower contact" tooth 23, nor can it hold the tooth 26 which, it will be noted, is the first with which it has to contend. Thus, since the pawl 14 operates to rotate the wheel only the space 75 of a single tooth at each impulse, and since the pawl 20 cannot engage the tooth 26, it follows that, so long as the pawl 20 is held elevated by the hook 28, impulses on the line will produce only a back and forth motion of the wheel through the space of a single tooth. Now, in order to cause the wheel to progress through its whole phase, means are provided whereby an impulse of sufficient duration, with the pawl 14 depressed, will cause the pawl 20 to be dropped in position to engage the base of the tooth 26, and also the bases of any "lower contact" teeth. For this purpose the following means are employed: Upon a rock shaft 30, at the 80 rear of the frame, is fixed a forwardly extending lever 31, to the free end of which is pivoted a frame 32 carrying an inertia time wheel 33, the hub 34 of which rests upon an inclined track 35 and is adapted 85 to slide or roll thereon. The inclination of the track 35 is adjustable through the medium of slot 36 within which the forward end of the track is secured by clamp 37. The wheel 33 is held near the upper end of the 90 track by an arm 38, fixed to the impelling lever 13 so that each time said lever is depressed the wheel 33 will begin to roll slowly down the track 35 only to be returned quickly when the lever 13 rises. If the impelling lever is depressed long enough, the 95 wheel 33 will roll down the track 35 sufficiently far to permit the frame 32 to engage the end of a lever 39 fixed to the rock shaft 29 to which the hook 28 is secured. 100 This action throws the hook 28 rearwardly away from the catch 27 so as to release the pawl 20 and is accomplished only in the event of a long impulse. This being given, 105 the tooth 26 is engaged and the wheel held 110 against return.

It will be noticed that, in the arrangement or combination of forms of teeth present in the control wheel shown, the cut-away tooth 26 is followed immediately by two "upper contact" teeth. Therefore, when the pawl 14 descends again to step the wheel 7 forward, the first of these teeth will lift the catch 27 above the hook 28; which meanwhile has returned to normal position, 120 whereupon the catch, dropping upon the hook will come into holding contact with the first of the "upper contact" teeth, holding the wheel against return. This impulse must be short, else the wheel 33 will roll suffi- 125 130

ciently far to remove the hook and permit the pawl 20 to ride off the inclined portion of the tooth. One more short impulse, following the one just described without appreciable intermission, will cause the wheel to be advanced. Since, now, the next tooth, as 23, to be engaged by the pawl 20 is a "lower contact" tooth, then the succeeding impulse must be of relatively long duration so as to permit the pawl 20 to drop into holding engagement with the flat surface of said tooth. When the wheel is again stepped forward, the next succeeding tooth, which is an "upper contact" tooth will again lift the pawl so that the catch 27 will be above the hook 28. This impulse being short and being followed by two short impulses and one long impulse, without appreciable intermission, brings the beveled teeth 25 into position opposite the pawl 20. The last of these impulses must be relatively long for the reason that the parts have now assumed position to close a contact for operating the electro-magnet signal as will be hereinafter explained. When the pawl 14 returns to normal, the beveled portion of the tooth 25 will push the lever 21 laterally, and the pawl 20 will be entirely disengaged from the teeth of the wheel and allow the latter to return to normal. It should be borne in mind that, with the pawl 20 in contact with the retaining surface of any one of the "upper contact" teeth as 24, if the time wheel 33 is allowed to complete its travel, then the hook 28 will be removed from beneath the catch 27 so that the pawl 20 will drop, and, upon the return of the pawl 14 to normal, the pawl 20 will ride off the cut-away or inclined portion of such tooth and permit the wheel to return immediately to its original position. The same result will obtain if a short impulse be given while the pawl 20 is opposite a "lower contact" tooth.

An illustrative object of the device so far described, is to cause the closing of a normally open circuit, and this end is attained as follows: Carried upon the shaft 30 is a spring contact arm 40, which projects upwardly into co-operative relation with an adjustable, relatively stationary, contact 41 carried by an insulating block 19 fixed between the side pieces 4 and 5 of the frame. Since the shaft 30 is controlled in its movements by the movements of the wheel 33 along the inclined track 35, it follows that the end of the contact arm 40 will be permitted to engage the contact 41 only when the wheel 33 moves downwardly throughout substantially its entire travel. Short impulses, permitting little or no movement of the wheel, will therefore not appreciably move the arm 40, while the relatively long impulses will. Fixed to the pivot end of the arm 40, and extending forwardly, is a relatively rigid arm 42, the front end of which

stands above a disk 43 carried by the shaft 6, said disk having a recess 44 at one point in its periphery. The free end of the arm 42 is bent downwardly as at 45 and adapted to engage the annular surface of the disk 70 for positively preventing premature engagement of the contacts 40 and 41, such as would occur during any long impulse either for operating this particular selector or for operating some other selector on the line, at all times except when the recess 44 is beneath the end 45 of the arm. The recess 44 is so positioned as to assume a position beneath the end 45 of the arm coincident with the completion of a selected series of impulses. 75 For instance, its position, in the structure illustrated, is such as to reach the end of the arm at the same time that the tooth 25 of the control wheel reaches its position opposite the pawl 20 so that during the time that the impulse, which moved the control wheel into this position, continues, the end 45 of the arm stands in the recess 44 and thus permits sufficient movement to bring the free end of the arm 40 into engagement with the contact 41. In order to permit of a slight movement between the shaft 30 and the arms 40 and 42 said arms are loose upon the shaft and an arm 46 is fixed to the shaft having a turned end portion extending beneath the 80 arm 42. A similar arm 47 is fixed to the shaft 30 having an end portion turned into position above the arm 42. The space between the turned portions of the arms 46 and 47, through which the arm 42 projects, 85 is sufficient to permit of the desired lost motion. The arm 46 serves to raise the arm 42 so that its end portion 45 does not normally rest upon the surface of the disk 43. The arm 47 serves to compel downward movement of the arm 42. A weight 48 is carried by the free end of the arm 42 for producing a more positive contact between the members 40 and 41 when the end 45 is within the recess 44 of the disk. 90

Fixed upon the shaft 6 is an arm 49 which, when the control wheel is returned to normal by the spring 8, will strike the inclined forward face of the lever 21 and raise the catch 27 above the hook 28. An 115 inclined pin 50 on the wheel 7 also engages the end of the lever and more positively moves the same laterally to a position with the pawl 20 above the teeth of the wheel. In the structure illustrated, as in the specific 120 application referred to, I also provide means whose function it is to return the control wheel to its normal position automatically in case said wheel has not been stepped forward sufficiently to bring its inclined tooth 125 25 into action when the impulses cease, as upon the happening of a break in the line, or at the end of a predetermined time after impulses used for operating other selectors on the line have ceased. To this end I have 130

provided upon the opposite side of the frame, from that occupied by the timing wheel 33, a second timing wheel as 51 which controls means for disengaging the pawl 20 from the teeth of the control wheel 7 as follows: An arm 52 is fixed upon a short shaft 53 journaled at the side of the frame piece 5, and to its outer end is pivoted a frame 54, to the lower end of which the wheel 51 is rotatably mounted with its shaft or hub 55 engaging, and movable along an inclined track 56, all of which structure is similar to that already described upon the opposite side of the machine. The inclination of the track 56, relative to the horizontal, is opposite to that of the track 35 and the wheel 51 is adapted to be slid upwardly along said incline by means of arm 57 secured to the forward end of the impelling lever 13. Upon each downward movement of said impelling lever the wheel 51 will be moved backward up its track. When the impelling lever rises, at the end of each impulse, the wheel 51 will roll slowly down the track, and if the lever is allowed to remain lifted for a sufficient length of time the wheel will roll to its lowest point.

Upon a suitable bracket 58 fixed to the side frame 5 is a pivotally mounted lever 59 which extends forwardly and is adapted to swing in a horizontal plane and has its free end bent inwardly toward the forward end of the lever 21. Extending laterally of the lever 59 and movable therewith, with bell crank action, is a second lever 60 which projects through the frame piece 5 and has its free end bifurcated and straddling a cross member 61 on the frame 54 as shown in Fig. 21. When the frame 54 moves forward the bifurcated end of the lever 60 is correspondingly moved and the bell crank action imparted to the lever 59 causes the free end of the latter lever to be moved toward the lever 21. If at this time the lever 21 is lowered, so that the pawl 20 is in engagement with any one of the teeth, then the lever 59 will force the lever 21 laterally and disengage the pawl 20 and thus allow the control wheel to reassume its normal position. The arm 49 and pin 50 carried by the control wheel will raise the lever 21 so that its forward end will be free of the end of the lever 59. Obviously, each depression of the impelling lever 13, operating through the arm 57, will move the lever 59 away from the lever 21 so as not to interfere with the movements of said lever 21 so long as the impelling lever is depressed and for a given interval of time thereafter. Thus, when the impelling pawl has been allowed to rise, and there is no succeeding downward movement for a limited period of time, then the timing wheel 51 will roll down its track and the frame 54 will force

the lever 59 inward and remove the pawl 20 so that the wheel 7 will return to normal. This action will take place in every selector at any time when the impelling lever is allowed to stand at normal for a given period. In order to permit the catch 27 to drop off the hook 28 when the lever 21 is moved laterally away from the control wheel a cut-away portion 62 is provided, intermediate the end of the catch and its point of connection with the lever 21.

So far as has been already described, the construction and operation of the present selector is substantially the same as that shown in the particular application above referred to. In order to provide that a single unitary selector may be capable of effecting selective operation of a plurality of signals or the like, I have provided means which will operate in response to impulse characteristic for placing into operation any one of a plurality of signal devices without interfering with or operating any of the other signal devices. Here, it may be pointed out that the closing of the electric circuit through the contacts 40 and 41 above described, is simply an exemplary illustration of one means which may be chosen to be set in signaling position by the devices described. The arm 40 might serve to operate any other suitable device.

Exemplifying the further use of the device I have chosen to illustrate a second electric contact which, of itself, is controlled in a manner exactly similar to that already described. In carrying out this idea, the control member 7 has its teeth so formed as to release the pawl 20 at any one of a plurality of points, determined by the position of said pawl in relation to said tooth, and for each point of release the shaft 6 is provided with one disk 43, each of said disks being provided with a recess 44 in its periphery. A pair of arms 40, 42 is provided, upon the shaft 30, for each of the disks 43, and the recesses 44 are spaced circumferentially apart so that preferably only one of said recesses will assume a position beneath the bent end 45 of its corresponding arm 42, at any one time. In the structure illustrated I have shown simply two of the disks 43, with corresponding arms 40 and 42 and contacts 41. One of these disks has its recess 44 positioned to receive the end of the arm 42, when the disk and control wheel have been rotated through the full extent of their movements. That is, when the tooth 25 of the control wheel is opposite the pawl 20, as has already been described. This position was reached in consequence of one long impulse (the regular starting impulse), two short impulses followed by a third long impulse (with the pawl 20 engaging the tooth 23), three quick impulses followed immediately by a long

impulse of a duration corresponding to the desired duration of the signal, (the tooth 25 is opposite the pawl 20). After the tooth 23 passed the pawl 20 said pawl was free to disengage itself from the wheel at any of the teeth intermediate the teeth 23 and 25, provided a long impulse had been given which would have removed the hook 28. It has been shown that this hook is automatically removed by the continued downward travel of the wheel 33 with each long impulse, and also that the downward travel of said wheel rocks the shaft 30 and lowers all of the arms 42 on to the peripheries of the disks 43. If a recess 44 is positioned to stand beneath one of the ends 45 of said arms, coincident with the giving of a long impulse, while one of the "upper contact" teeth, intermediate the teeth 23 and 25, is opposite the pawl 20, then said arm will be permitted to lower and bring its corresponding arm 40 into position for operating the signal. Following this, immediately the long impulse terminates, the pawl 20, being then opposite the lower portion of the "upper contact" tooth, will cam laterally and permit the wheel to reassume its normal position. This action would take place in consequence of a long impulse at any time when an "upper contact" tooth is opposite the pawl 20, provided a disk having a recess 44, is arranged to receive the end of a lever 42 at the time said long impulse is given either before or after the tooth 23 passes.

In the structure shown the recess 44 on the second disk 43 is positioned so as to receive the end 45 of the associated arm 42 at the time of the first impulse after the tooth 23 is passed, thus providing the necessity for a properly placed long impulse (at tooth 23) in order to operate either of the circuit closers of this particular instrument.

The slight modification referred to in Fig. 9 appertains to the arrangement of the arms 46 and 47 for lifting and depressing arms 42. This figure indicates the use of a single arm 63 fixed to the shaft 30 between two arms 42 and having a cross head 64 bifurcated at its opposite ends to straddle the arms 42. The operation of this improved selector, whereby a selected one of a plurality of signals, is operated at a selected station is as follows: Supposing, a group of stations to be provided upon a single line with one unitary selector at each station, then the teeth upon the control wheels 7 of the several selectors are cut in such manner that each of said wheels will be stepped forward by a series of codal impulses different from any of the others of said wheels. All of the instruments will be arranged in a well known manner so that their magnets are all energized simultaneously by impulses impressed upon the line by automatic senders, or otherwise. Supposing, now, that the

station, in which the selector disclosed herein is placed, is to be exclusively called by one or the other of its signals: (it may be here noted that the several signals adapted to be set in operation by the single unitary selector shown, may comprise, for instance, bells in different parts or departments of an institution, or they may comprise means for designating the particular individuals intended to be interested, or they may be applicable for use in various other ways, and for a variety of purposes which will be apparent to those skilled in the art), the instruments all being in normal position, the operator will first hold the circuit, through all the magnets 9, closed for a sufficient length of time to permit the several timing elements 33 to remove the several hooks 28 from retaining position beneath the catches 27 so that pawls 20 of all of the selectors will drop upon the teeth 26 of the wheels 7. Three impulses will now be produced, the first two of short duration, but the third sufficiently long to allow the pawl 20 to fall behind the engaging face at the lower portion of the "lower contact" tooth 23. For operating one of the signals at this station a single long impulse will now be given. For operating the other of the signals at this station, four impulses will be given; the first three being short and the last long. In the former instance, the single long impulse will move the first "upper contact" tooth 24, after tooth 23, into position opposite the pawl 20, the hook 28 will be removed, and the pawl 20 will fall to the bottom of said tooth and will cam off thereof, immediately the impulse ceases. In the latter instance, the short impulses, following the long impulse at tooth 23, will retain the pawl 20 in its upper position until the long impulse is given at tooth 25, when the pawl will drop and permit return of the wheel to normal upon cessation of the impulse. In each instance, one of the disks 43 will be in position so that its recess 44 is beneath one of the arms 42. It will be apparent that the control wheels 7 of the other instrument on the line will have either returned to normal, or at least will not have one of its disks 43 arranged to permit contact of the circuit closures therein, and that consequently only the instrument in the present station will be operated and the particular signal desired in that instrument only will be operated. The tooth 25, beveled throughout its entire engaging surface, is invariably placed at the end of the series of prepared teeth, and its office is to positively prevent a retaining engagement of the pawl 20 while the impelling pawl 14 is being raised to engage a succeeding tooth. Its cam face removes the pawl entirely from engaging relation with the teeth whether said pawl be in its raised or its lower pos-

tion. It will be understood, of course, that the contacts 41 are electrically connected, as by wires 65—66, with binding posts 67 and 68 preferably outside of the hood 2, while the opposite pole of the circuit may be grounded in the frame of the device.

From the foregoing it will be apparent that I have improved my device so as to be able to operate a plurality of signals, from a single selector, in response to impulse characteristic, being susceptible to operation for any number of times without affecting the operation of any of the others of said signals, and that a great variety of combinations may be made for operating a reasonably great number of signals from the single unitary selector, and that the number of combinations of upper and lower contact teeth possible on the control wheels of the several machines, is not lessened by the presence of the plurality of divisions within a given selector.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which as a matter of language, might be said to fall therebetween.

Having thus described my invention what I claim as new and desire to obtain by Letters Patent, is:

1. In a device of the class described, the combination of a single rotatable control member adapted to be rotated by a series of impulses and to be selectively rotated into a plurality of distinct operative positions and a plurality of circuit closers rotated with said control member and adapted to be operated selectively one corresponding to each operative position of said control member.

2. In a device of the class described, the combination, in a unitary structure, of a plurality of circuit closers, a control member for placing all of said circuit closers in position for circuit closing movement and means operated by said control member for preventing all but one of said circuit closers from closing its circuit for each selective position of said control member.

3. In a device of the class described, the combination of a control member adapted to be stepped by a series of impulses, means for stepping said member, a plurality of normally open circuit closers, each comprising a movable contact and a fixed contact

and means under the control of said control member whereby one, only, of said circuit closers is made operative when said control member has been stepped to a selected position.

70

4. In a device of the class described, the combination of a control member adapted to be selectively stepped to a plurality of operative positions by series of impulses, means for stepping said member, a circuit closer for each selective position of said member, a single time element for operating said circuit closers and means under the control of said control member for selecting the circuit closer for operation at each selective position of said control member.

75

5. In a device of the class described, the combination of a control member adapted to be selectively stepped by a series of impulses, means for stepping said member, a plurality of circuit closers adapted to be placed in position for circuit closing movement, a single time element for operating said circuit closers in accordance with the number of steps through which said control member has moved and means controlled by said control member for permitting only one of said contact closers to operate for each selective position of said control member.

85

6. In a device of the class described, the combination of a control member adapted to be selectively stepped to a plurality of operative positions by series of impulses, means for stepping said member, means opposing the stepping of said control member, means, the operation of which is determined by the length of impulse to render said last named means inoperative, means for restoring said opposing means to operative condition when the control member has been stepped through a phase of movement, a plurality of circuit closers, according to the selected position of said control member and means operable by said control member for preventing all but one of said circuit closers from closing its circuit at each selective position of said control member.

95

7. In a device of the class described, the combination, in a unitary structure, of a single control member operated by a series of impulses, means for operating said member, a plurality of circuit closers adapted to be placed in position for circuit closing movement and means controlled by said control member for preventing all but one of said circuit closers from moving into circuit-closing position at each selective position of said control member.

105

8. In a device of the class described, the combination, in a unitary structure, of a single control member operated by a series of impulses, means for operating said member, a plurality of circuit closers adapted to

110

120

125

130

be placed in position for circuit closing movement and means movable with said control member for retaining said circuit closers against circuit closing movement, said 5 means being adapted to selectively permit movement of said circuit closers into circuit closing position.

9. In a device of the class described, the combination of a control wheel adapted to 10 be rotated into any one of a plurality of different positions in response to different series of codal impulses, means for rotating said member, a plurality of circuit closers one for each of the positions into which said 15 control wheel may be thus rotated and means movable with said control wheel for maintaining all of said circuit closers open but adapted to permit closing of one only of said circuit closers as said control wheel 20 is selectively moved into said different positions.

10. In a device of the class described, the combination of a control wheel adapted to be rotated into any one of a plurality of different positions in response to series of impulses, means for rotating said member, a plurality of circuit closers one for each of the positions into which said control wheel 25 may be thus rotated, means movable with said control wheel for maintaining all of said circuit closers open but adapted to permit closing of one only of said circuit closers as said control wheel is selectively moved into said different positions and a time element adapted to retain said circuit closers 30 out of coöperative relation with said last named means as some of said positions are passed.

11. In a device of the class described, the combination of a control wheel adapted to 40 be rotated into any one of a plurality of different positions in response to different series of codal impulses, means for rotating said member, a plurality of circuit closers one for each of the positions into which 45 said control wheel may be thus rotated, means movable with said control wheel for maintaining all of said circuit closers open but having cut away portions adapted to permit closing of one only of said circuit 50 closers for each position of said wheel and a time element adapted to retain said circuit closers out of coöperative relation with all of said cut away portions except a selected one as determined by the particular series of codal impulses. 55

12. In a device of the class described, the combination of a single rotatable control member adapted to be rotated by a series of impulses and to be selectively rotated 60 into a plurality of distinct positions, means for rotating said member, a plurality of circuit closers, means rotatable with said control member for controlling said circuit closers whereby said circuit closers are 65 adapted to be operated one corresponding to each of the positions of said control member and means for returning said control member to normal after the operation of any one of said circuit closers. 70

In testimony whereof I affix my signature in the presence of two witnesses.

WILLIAM E. HARKNESS.
